UNITED STATES PATENT OFFICE.

ERNEST EVERETT EINFELDT, OF DAVENPORT, IOWA, ASSIGNOR TO G. WATSON FRENCH, JOSEPH L. HECHT, AND W. H. STACKHOUSE, ALL OF DAVENPORT, IOWA, COMPOSING THE FIRM OF FRENCH & HECHT, OF DAVENPORT, IOWA.

METHOD OF MAKING METAL WHEELS.

Application filed June 10, 1924. Serial No. 719,058.

To all whom it may concern:

Be it known that I, ERNEST E. EINFELDT, a citizen of the United States, residing at Davenport, in the county of Scott and State of Iowa, have invented certain new and useful Improvements in Methods of Making Metal Wheels, of which the following is a specification.

This invention relates to the making of metal wheels and consists of an improved method of connecting the parts of the wheel together, with the view to producing a wheel of strong and durable construction, of true circular form, and in which the spokes will be under tension or pull.

In carrying out the invention in the preferred method of procedure, spokes are provided, and an open ended rim is also provided having holes to receive the spoke ends, which holes are of greater diameter than that of the spoke ends, and the rim is assembled on the spokes with the ends of the latter seated in said holes so that there is permitted a limited circumferential play of the assembled rim relative to the spokes. The ends of the rim are now connected together, preferably by butt-welding, which action will result in a slight decrease in the diameter of the rim, which decrease in diameter, will, by reason of the circumferential play of the rim, be permitted without bringing any lateral stresses on or causing distortion of the spokes; and finally the spoke ends are rigidly connected with the rim, as by upsetting or heading operations, or the like.

The method of procedure above outlined is applicable as well in the connection of the spokes to the hub, by employing an open ended hub shell with holes of greater diameter than that of the spoke ends to receive the latter, and permit circumferential play of the hub shell, the decrease in diameter of the hub shell due to the butt-welding of the same being permitted by reason of said play without distortion of the spokes. However in practising my invention, I prefer to apply the same in connecting the spokes to the rim of the wheel, and in the following detailed description of the invention and in the drawings illustrating how the same is carried into effect, the invention is so disclosed.

In the accompanying drawings:

Fig. 1 is an elevation of a wheel hub with 55 spokes attached thereto.

Fig. 2 is an elevation of an open ended 55 rim.

Fig. 3 is a view in elevation showing the rim assembled on the spokes, with the ends of the rim abutting preparatory to being 60 welded.

Fig. 3^a shows an enlarged detail of the rim and spoke connection.

Fig. 4 is a similar view showing the rim after being welded, and with adjacent spoke 65 ends in operative relation to heating and heading devices.

Fig. 5 is an elevation of the completed 70 wheel resulting from the practice of my method.

Fig. 6 is a detail of the heading device as applied to the spokes.

Referring to the drawings:

In carrying my improved method into effect in the preferred manner, I first provide as shown in Fig. 1, spokes 1 having on their outer ends reduced tenons 2, and shoulders 3 at the base of the tenons. These spokes are previously fixedly connected at their inner ends to a hub 4, either by casting the hub on the spokes, or by heading the spokes in the hub, or by other suitable means, this construction producing what is known in the art as a "wheel spider." I next provide an open ended wheel rim 5 as 85 shown in Fig. 2, in which rim, holes 6 are formed to receive the spoke tenons 3, which holes are of a diameter greater than that of the tenons, the purpose of which will 90 presently appear. The rim is next assembled on the spokes with the tenons seated in the holes as shown in Fig. 3, the size of the rim being such that when thus assembled and with its ends abutting as shown at 7, the inner side of the rim will be disposed outward of and free of contact with the shoulders 3 on the spokes. The rim as 95 thus assembled on the spokes is permitted a limited amount of circumferential play or movement relative to the spokes, due to the clearance between the exterior of the tenons and the interior of the holes. I next connect the ends of the rim together to make 100 the same continuous, and this I prefer to

effect by butt-welding, in which operation the two ends of the rim are heated, and in order to bring about a good joint or weld, the ends are pressed against each other with sufficient force to throw up a flash or burr 8 as shown in Fig. 4. Due to the formation of this burr, the rim will decrease in diameter, but by reason of the relative play to the spokes, it will take its final and definite size without bringing any lateral stresses on or causing distortion of the spokes. In the decrease of the diameter of the rim in the welding operation as described, its inner side will be brought closer down to the shoulders 3 on the spokes, and perhaps according to conditions, will seat loosely or lightly thereon; or under other conditions it may approach the shoulders very closely without contacting with the same. In the next and final step of the method, the spoke ends or tenons are headed down on the rim, with the result that the rim will be forced tightly against the shoulders on the spokes and seated solidly against the same, and the spokes will be rigidly and fixedly connected to the rim.

This heading of the spoke ends may, when the spokes are formed of relatively soft metal, be effected without the application of heat, by means of a suitable heading or upsetting tool or device, many forms of which are well known in this art; but when the spokes are formed of harder metal, such as high carbon steel for instance, it will be necessary to heat the spokes before heading the same. In such cases I prefer to heat and head adjacent spoke ends simultaneously, and repeat such simultaneous operations on the successive spokes, so that while one spoke end is being heated, the previously heated spoke end will be headed. These operations may be conveniently performed by supporting the assembled wheel as shown in Fig. 4 so that it may be turned on its axis, and by providing an electric heating device 9, and a heading device 10, the said two devices being so spaced and positioned that when one spoke end is in operative relation to the heating device, the next adjacent spoke end will be in operative relation to the heading device. With the parts positioned as shown in Fig. 4, while the tenon of spoke A is being heated, the tenon of the adjacent spoke B will be headed, and on the completion of such simultaneous operations, the wheel is turned to bring spoke B into operative relation to the heating device, and to bring the next spoke C into operative relation to the heating device, and these operations are repeated on the successive spokes until they have all been fastened rigidly to the rim and the formation of the wheel completed.

In the heading down of the spoke ends, the rim will be caused to seat tightly and solidly against the spoke shoulders as above

described, and will be forced inwardly slightly at points in its circumference corresponding to the location of the spoke shoulders, thereby causing a pull to be exerted on the spokes and producing a tension wheel, but without destroying the general circular form of the rim.

The welding of the rim ends may be effected in any suitable manner and by the employment of any suitable device which will bring about the butt-welding of said ends. I prefer however to employ electric welding means for this purpose, many forms of which devices are well known in the art.

In the foregoing description and accompanying drawings I have set forth the preferred manner of practising my improved method, but it will be understood that the invention is not limited to the precise method of procedure set forth, nor to the particular construction and form of the parts of the wheel illustrated, as the method of procedure may be varied within the skill of the mechanic without departing from the limits of the invention; and it will be understood that the invention is not limited to the particular steps set forth, except in so far as such limitations are specified in the claims.

Having thus described my invention, what I claim is:

1. The method of making metal wheels, which consists in assembling an open wheel member on spokes and providing for circumferential play of the assembled wheel member relative to the spokes, connecting the ends of the wheel member together whereby the circumferential play of the wheel member will prevent lateral stresses on the spokes, and finally fastening the spokes rigidly to said wheel member.

2. The method of making metal wheels, which consists in providing a hub and connected spokes, providing an open rim, assembling the rim on the spokes and providing for circumferential play of the assembled rim relative to the spokes, connecting the ends of the rim together whereby the circumferential play of the rim will prevent lateral stresses on the spokes, and finally fastening the spokes rigidly to the rim.

3. The method of making metal wheels, which consists in providing spokes, providing an open ended wheel member having holes of greater diameter than that of the spoke ends, assembling the wheel member on the spokes with the ends of the latter seated in said holes, whereby circumferential play of the assembled wheel member relative to the spokes will be permitted, butt-welding the ends of the wheel member, and finally fastening the spoke ends rigidly to the wheel member.

4. The method of making metal wheels,

- which consists in providing spokes, providing an open ended rim having holes of greater diameter than that of the spoke ends, assembling the rim on the spokes with the 5 ends of the latter seated in said holes, whereby circumferential play of the assembled rim relative to the spokes will be permitted, butt-welding the ends of the rim, and finally fastening the spoke ends rigidly to the rim.
- 10 5. The method of making metal wheels, which consists in providing spokes having shoulders and end tenons, providing an open ended wheel member having holes of greater diameter than that of the tenons, assembling 15 the wheel member on the spokes with the tenons seated in said holes, whereby circumferential play of the assembled wheel member relative to the spokes will be permitted, butt-welding the ends of the wheel 20 member, and finally heading the spoke tenons down on the rim to seat the latter against the shoulders and effect the rigid connection of the spokes with the wheel member.
- 25 6. The method of making metal wheels, which consists in providing spokes having shoulders and end tenons, providing an open ended rim having holes of greater diameter than that of the tenons, assembling the rim 30 on the spokes with the tenons seated in said holes, whereby circumferential play of the assembled rim relative to the spokes will be permitted, butt-welding the ends of the rim while the latter is free to move circumferentially relative to the spokes, whereby 35 the rim will assume its final and definite diameter without distortion of the spokes, and finally heading the tenons down on the rim and seating the latter against the
- shoulders to effect the rigid connection of 40 the spokes with the rim.
7. The method of making metal wheels, which consists in providing spokes, providing an open ended rim having holes of greater diameter than that of the spoke ends, 45 assembling the rim on the spokes with the spoke ends seated in said holes, whereby circumferential play of the assembled rim relative to the spokes will be permitted, butt-welding the ends of the rim, simultaneously heating one spoke end and heading the previously heated spoke end to secure 50 the spoke to the rim, and repeating said simultaneous operations on the successive spoke ends. 55
8. The method of making metal wheels, which consists in providing spokes having shoulders and end tenons, providing an open ended rim having holes of greater diameter than that of the tenons, assembling the rim 60 on the spokes with the tenons seated in said holes, whereby circumferential play of the assembled rim relative to the spokes will be permitted, butt-welding the ends of the rim while the latter is free to move circumferentially relative to the spokes, whereby the rim will assume its final and definite diameter without distortion of the spokes, simultaneously heating one spoke tenon and heading the previously heated tenon down on the 65 rim to seat the rim against the spoke shoulder and secure the spoke rigidly to the rim, and repeating said simultaneous operations on the successive spoke tenons. 70
- In testimony whereof, I have affixed my 75 signature hereto.

ERNEST EVERETT EINFELDT.
